H. V. A. LORING.

DRESSING CASE.

APPLICATION FILED MAR. 17, 1913.

1,074,634.

Patented Oct. 7, 1913.

UNITED STATES PATENT OFFICE.

HELENE V. A. LORING, OF CHICAGO, ILLINOIS.

DRESSING-CASE.

1,074,634.

Specification of Letters Patent.

Patented Oct. 7, 1913.

Application filed March 17, 1913. Serial No. 754,941.

To all whom it may concern:

Be it known that I, HELENE V. A. LORING, a citizen of the United States, and a resident of the city of Chicago, county of 5 Cook, and State of Illinois, have invented certain new and useful Improvements in Dressing-Cases, of which the following is a specification.

My invention relates to improvements in 10 dressing cases and has for its object the production of a case of this character which will be provided with a cover adapted when in open or upright position to serve in the capacity of a looking glass.

15 A further object is the production of a case as mentioned in which the cover will be of a sectional character adapted for vertical adjustment and in which the sections may be adjusted laterally or extensibly and 20 angularly so as to permit of a view from any angle.

A still further object is the production of a dressing case which will be of durable and economical construction, neat and finished in appearance, and efficient in use. 25

Other objects will appear hereinafter.

The invention consists in the combinations and arrangements of parts hereinafter described and claimed.

30 The invention will be best understood by reference to the accompanying drawings forming a part of this specification, and in which—

Figure 1 is a perspective view of a dressing case embodying my invention, the cover of the case being shown in open position arranged for use as a looking glass, Fig. 2 is a top plan view of the dressing case, showing the cover of the case in closing position, Fig. 3 is a front elevation of the main or central section of the cover of the case, showing the same in upright position, a fragment only of the body of the case being illustrated, Figs. 4 and 5 are vertical sections taken on substantially lines $x-x$ and $y-y$, respectively, of Fig. 3, and Fig. 6 is an enlarged fragmentary horizontal section taken on substantially line $z-z$ of Fig. 3.

The preferred form of construction as 50 illustrated in the drawing comprises a dressing case consisting of a rectangular body 1, which is open at its upper side, the interior of said body being divided by partitions 2 into a plurality of independent 55 compartments for the reception of the various articles which are used or carried in

cases of this character. Provided at the upper side of the body 1 is a cover or closure sectional in character consisting of the main or central section 3 which is hingedly secured to the body 1 and end sections 4. The under sides of the sections 3 and 4 are provided with mirrors 5 so that, when said sections are in vertical position, the same will be adapted to serve in the capacity of looking glasses as will be readily understood. The sections 4 are pivotally and extensibly connected with the section 3 by means of lazy-tong members 6, the use of connecting means of this character permitting of the 60 said sections 4 being arranged coplanar with the section 3 for entirely closing the upper side of the casing 1, when the device is not in use, and of said sections 4, when in upright position, to be moved laterally and adjusted angularly in order to afford a view of the user at any angle. The section 3 is provided at its lateral edges with outwardly projecting dowel pins 7 adapted, when the cover sections are in closing position, to engage corresponding recesses or sockets provided in the contiguous edges of the sections 4 in order to securely hold the cover sections in coplanar positions as will be readily understood.

The hinged connection of the main cover section 3 with the body 1 is effected by means of elongated bars 8, the rearward ends of which are pivotally or hingedly connected at 9 with plates 10 which are rigidly secured upon the upper edge 1' of the rearward wall of the casing body. The outer or free ends of the bars 8 slidably engage loops of socket members 11, which are secured upon the upper side of the section 3 adjacent the lateral edges thereof. The arrangement as will be observed, is such that the cover section 3 will be free to swing about the points 9 and when said cover section is in upright position, the same will be permitted to slide downwardly upon the bars 8 in order to rest upon the edge 1' of the body 1. The edge 1' projects above the upper side of the case body 1 so that when the cover is in closing position, the upper side of the latter will be flush with the said edge 1'. Also the arrangement is such that, when the cover section 3 is in upright position, and resting upon the edge 1', the front side of said cover will be flush with the corresponding side of the rear wall of the body 1. When the cover section 3 is

seated upon the edge 1', as just mentioned, it will be seen that the same will be locked against forward tilting. In order to prevent rearward tilting of said cover section, when 5 in this position, the rearward ends of the bars 8 are provided with extensions 12 adapted, when said bars are rocked to upright positions to swing into sockets 13 formed in the plates 10, and when said bars 10 are in upright position, to engage against the front sides of said sockets in order to limit the swinging movement of said bars. Thus when the cover section 3 is seated upon the edge 1' the same will be locked in upright 15 position against forward or rearward tilting. When the cover is in closing position the extensions 12 of the bars 8 assume a horizontal position closing the sockets 13 thus conducting to neatness in construction.

20 Arranged medially upon the upper side of the cover section 3 is a rack bar 14 which is slidably mounted in a guide 15 rigidly secured to said section. Provided in the edge 1' of body 1 is a socket 14' adapted, 25 when the cover section 3 is in upright position to register with and receive the lower end of rack bar 14. Said socket and said end of said rack bar are tapered as shown so that when said end of said bar engages 30 said socket a secure connection will be insured. Rotatably mounted at the upper side of the section 3 adjacent the rearward or pivoted edge thereof is a pinion 16 which is inclosed in the guide member 15 as clearly 35 shown in Figs. 4 and 6. The pinion 16 meshes with the rack bar 14 and so that by rotating said pinion vertical adjustment of the cover section 3 and hence the cover sections 4 carried by said section 3, may be 40 effected. The stem 17 of the pinion 16 is provided at its forward end with an exteriorly positioned hand wheel 18 through the medium of which said pinion may be manually rotated in order to effect vertical adjustment of the cover. Locking of the cover 45 in positions of vertical adjustment is secured through the medium of a pin 19 the rearward headed end of which is slidably mounted in an elongated slot 20 provided in a plate 21 secured upon the front side of the section 3 as shown. The pin 19 is adapted to be moved to engage between the spokes of the hand wheel 18 in order to prevent rotation thereof and hence to lock the cover 50 in any position to which the same may be adjusted, as will be readily understood. In order to insure against accidental disengagement of the spokes of wheel 18 from the pin 19, the inner end of the slot 20 is provided with a notch or enlargement 22 for the reception of said pin, the latter being pressed into engagement with said notch 22 through the pressure of the spokes of the wheel 18 thereon when the cover is in elevated 55 position. When it is desired to re-

lease the cover in order to lower the same, the pin 19 may be slid laterally out of the path of the spokes of the wheel 18.

With a construction as set forth then it will be seen that a cover is provided which, 70 when in upright position is adapted for service as a looking glass. Said cover in order to adapt the same for more effectual service as a looking glass, is sectionally formed, certain of the sections being arranged for extensible and angular adjustment. Also the cover is vertically adjustable so as to adapt the same to suit the convenience of the user. The construction is 75 neat and finished in appearance and will be 80 found of high efficiency in use.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 85 the appended claims.

Having described my invention what I claim as new and desire to secure by Letters Patent is:

1. A dressing case comprising a hollow 95 body having a compartment therein opening at the upper side of said body; a closure for said body; a hinged connection between said body and said closure permitting of vertical adjustment of said closure when the latter is in upright position; a rack and pinion for vertically adjusting said closure; and means for releasably locking said closure in positions of vertical adjustment, substantially as described.

2. A dressing case comprising a hollow body having a compartment therein opening at the upper side of said body; a closure for said compartment; a hinged connection between said body and said closure permitting of vertical adjustment of said closure when the latter is in upright position; a rack and pinion for vertically moving said closure; and means adapted for cooperation with said pinion for releasably locking said closure in positions of vertical adjustment, substantially as described.

3. A dressing case comprising a body having an open upper side; a cover for said body; a hinged connection between said body and said cover permitting of vertical adjustment of said cover, when the latter is in upright position; a rack bar slidably mounted in said cover; a socket provided in said body, one end of said rack bar 120 being adapted to releasably engage said socket when said cover is in vertical position; a pinion provided in said cover meshing with said rack bar whereby said cover may be moved vertically through rotation 130

of said pinion; and means for releasably locking said cover in positions of vertical adjustment, substantially as described.

4. A dressing case comprising a body having an open upper side; a cover for said body; a hinged connection between said body and said cover permitting of vertical adjustment of said cover, when the latter is in upright position; a rack bar slidably mounted in said cover; a tapering socket provided in said body, one end of said rack bar being correspondingly tapered for releasable engagement with said socket when said cover is in upright position to support said rack bar in upright position; a pinion mounted in said cover meshing with said rack bar whereby said cover may be moved vertically through rotation of said pinion; and means for releasably locking said cover in positions of vertical adjustment, substantially as described.

5. A dressing case comprising a body having an open upper side; a cover for said body; a hinged connection between said body and said cover permitting of vertical adjustment of said cover when the latter is in upright position; a rack bar slidably mounted in said cover; a socket provided in said body, one end of said rack bar being adapted to releasably engage said socket when said cover is in upright position; a pinion provided in said cover meshing with said rack bar whereby said cover may be moved vertically through rotation of said pinion; and means cooperating with said pinion for releasably locking said cover in positions of vertical adjustment, substantially as described.

6. A dressing case comprising a body having an open upper side; a cover for said body; a hinged connection between said body and said cover permitting of vertical adjustment of said cover when the latter is in upright position; a rack bar slidably mounted in said cover; a socket provided in said body, one end of said rack bar being adapted to releasably engage said socket when said cover is in upright position; a pinion provided in said cover meshing with said rack bar whereby said cover may be moved vertically through rotation of said pinion; a hand wheel connected with said pinion for manually rotating the latter; and means adapted for engagement with said hand wheel for releasably locking said cover in positions of vertical adjustment, substantially as described.

7. A dressing case comprising a hollow body having a compartment therein opening at the upper side of said body; a bar hingedly connected at one end to said body; a closure for said compartment; a slidable connection between said closure and the free end of said bar, said closure when in ver-

tical position, being adapted to rest at its lower edge upon the upper edge of said body 65 to prevent tilting of said closure in one direction; and means on said bar for preventing tilting of said closure in the opposite direction, substantially as described.

8. A dressing case comprising a hollow 70 body having a compartment therein opening at the upper side of said body; a bar hingedly connected at one end to said body; a closure for said body; a slidable connection between said closure and the free end of 75 said bar; said closure when in vertical position, being adapted to rest at its lower edge upon the upper edge of said body to prevent tilting of said closure in one direction; and a projection at the pivoted end of said bar 80 for preventing tilting of said closure in the opposite direction, substantially as described.

9. A dressing case comprising a hollow body having a compartment therein opening at the upper side of said body; a bar 85 hingedly connected at one end to said body; a closure for said compartment; a slidable connection between said closure and the free end of said bar, said closure, when in vertical position, being adapted to rest at its lower 90 edge upon the upper edge of said body to prevent tilting of said closure in one direction; and an extension at the pivoted end of said bar for preventing tilting of said closure in the opposite direction, said body being 95 cut away to afford clearance for said extension in the swinging of said bar, substantially as described.

10. A dressing case comprising a body having an open upper side; a cover for said 100 body, said cover consisting of a main section; end sections pivotally and extensibly connected with said main section; and a hinged connection between said body and said main section permitting of vertical adjustment of 105 the latter when in upright position, substantially as described.

11. A dressing case comprising a body having an open upper side; a cover for said body, said cover consisting of a main section and end sections pivotally and extensibly connected with said main section; mirrors provided at the under sides of said cover sections; a hinged connection between said body and said main cover section permitting 110 of vertical adjustment of the latter when in upright position; and means for locking said cover sections in positions of vertical 115 adjustment, substantially as described.

In testimony whereof I have signed my 120 name to this specification in the presence of two subscribing witnesses.
